ELIJAH WARE, OF BAYONNE, NEW JERSEY.

Letters Patent No. 68,015, dated August 20, 1867.

IMPROVEMENT IN MACHINERY FOR PROPELLING STEAM-CARRIAGES.

The Schedule referred to in these Letters Patent and making part of the same.

TO ALL WHOM IT MAY CONCERN:

Be it known that I, ELIJAH WARE, of Bayonne, Hudson county, New Jersey, have invented a new and improved Gearing for Steam-Carriages, etc.; and I do hereby declare that the following is a full, clear, and exact description thereof, which will enable others skilled in the art to make and use the same, reference being had to the accompanying drawings, forming part of this specification.

This invention relates a new and improved method of altering the speed and thereby increasing the power used in the propulsion of steam-carriages, and for other purposes; and it consists in a combination of wheels which operate so that the gear-wheels may be made to exert increased power when desired, as will be described more fully hereinafter.

Figure 1 is a vertical section through the line $x-x$, fig. 2.

Figure 2 is cross-section through the line $y-y$, fig. 1.

Similar letters of reference indicate corresponding parts.

A represents a shaft or the axle of a steam-carriage. B is a pulley, which is attached to a sleeve, B', through which the shaft or axle passes. C is a spur-gear wheel, which is attached to the sleeve B'. D is a reversing-wheel with ratchet recesses on its periphery, and which is moved around the sleeve B on its own centre marked D'. The mitre-gear, marked E, is attached to this reversing-wheel D. Within the pulley B there are four mitre-wheels, which engage with each other, as seen in the drawings. The three other mitre-gears are marked F, G, and H. F and H are attached to the pulley, and revolve on stud-pins which are secured to arms ff cast on the pulley B, as seen in the drawing. The inner ends of these stud-pins are secured to the sleeve B'. The mitre-wheel G is attached to a plate-wheel marked J, which is permanently attached to the shaft or axle A. K is a break-wheel, which is placed loosely on the shaft. It has a groove around its periphery, and is encircled by a band which is attached to a break-lever, the short end of which is seen at J', fig. 1. This break-wheel is connected with the plate-wheel J by jointed levers m and n , which levers operate eccentrics on the inner side of J. These eccentrics are blocks of metal, which, when turned by the levers, come in contact with the inner surface of the band-wheel or pulley B, either retarding or stopping the motion. P, fig. 2, is a double pawl, which is operated by the lever Q. These pawls engage with either side of the wheel, according to the direction which it is desired to have the machine run. The pawls may be placed with the wheel intermediate, in which case the whole arrangement revolves together. To diminish the speed one-half, and to double the power, it is only necessary to stop the wheel D by one of the pawls. The mitre-wheel E then stops also and becomes the fulcrum of the other gears.

I do not confine myself to this particular arrangement, as it will be seen that by varying the size and proportions of the mitre or bevel-gearing the power may be increased accordingly. The power can be taken either from the pulley B or the spur-gear wheel C, and the arrangement may be applied to lathes and other purposes, as well as to steam-carriages. In the latter application I have found it of great advantage in ascending heavy grades and in passing over rough and uneven roads with my steam-carriage, for which I have already received Letters Patent. The shaft A may either represent the axle or a counter-shaft, according as the power is applied.

Having thus described my invention, what I claim as new, and desire to secure by Letters Patent, is—

1. The combination of gear-wheels C E F G, arranged substantially as herein-described for the purpose specified.
2. I claim the running-wheel D, the break-wheel K, the pulley B, and the double ratchet P, in combination with the gear-wheels, substantially as described.
3. I claim the break-wheel K, in combination with the gear-wheels, as described.

The above specification of my invention signed by me this 21st day of March, 1867.

ELIJAH WARE.
